DESIGN FOR A BALANCE.

CHARLES E. HOFFMANN, OF PHILADELPHIA, PENNSYLVANIA.

Design No. 2,532, dated December 18, 1866.

The Schedule referred to in these Letters Patent and making part of the same.

TO ALL WHOM IT MAY CONCERN:

Be it known that I, CHARLES E. HOFFMANN, of the city and county of Philadelphia, and State of Pennsylvania, have invented a certain new and ornamental Design for Scales, or rather for the cases which enclose scales for weighing; and I do hereby declare that the following is a full and exact description thereof.

To enable those skilled in the art to manufacture the cases of scales according to my design, I will proceed to describe it by the aid of the accompanying figure, which forms a part of this specification.

The pans of the scales, and the indices, or small arrow-heads, which by their movement vertically past each other indicate the relative heights of the pans, are very conspicuously represented in the figure. This, and the stems or supports for the pans, are the only working portions of the scale which need be left unclosed.

A is a spread eagle surmounting the entire design. B is a cylindrical casing, which may receive a glass at each of its circular ends, in order to show the indices, and protect them from any accidental injury. C is a columnar casing with a niche, which contains an ornamental image, D. E is a pedestal quite massive in appearance, which connects the temple-like structure above, of the upper surface, F, of the main casing below. A portion of each end of the main casing is rounded as indicated by F'. G is an ornamental and slightly overhanging border. H are the perpendicular sides, and I an ornamental border which projects around the base of the main casing. J are legs made ornamental, and located at the corners, as represented. L is a centre-piece, and L¹ L² extensions in opposite directions, which form an ornament on each of the flat faces or sides of the main casing.

Having now fully described my ornamental casing for scales, what I claim as new, and desire to secure by Letters Patent, is—

The design here represented and described for a casing for scales. This I claim, whether the scales be constructed in accordance with my patent, above referred to, or in any other manner, and adapted to be contained in a casing of such design.

CHARLES E. HOFFMANN.
